His Attorney.

UNITED STATES PATENT OFFICE

PIETRO BOLIS, OF MILAN, ITALY, ASSIGNOR TO GENERAL ELECTRIC COMPANY, A CORPORATION OF NEW YORK

METHOD OF WINDING COILS

Application filed December 27, 1927, Serial No. 242,867, and in Italy December 28, 1926.

My invention relates to a method and apparatus for winding coils for electric apparatus such as transformers and more particularly to a method and apparatus for winding a stack of flat disc coils from a single unbroken or continuous conductor and with annular insulating collars interposed between adjacent coils of the stack. This type of disc coil stack has been used in the past to a large extent, successive coils being wound on a suitable form and alternately from their inside to their outside edges and from their outside to their inside edges to avoid the necessity of joints in the cross-over connections between coils. After winding each coil, a suitable flexible insulating collar has been placed next to it on the form, the collars being split at one side and spread open to permit them to be placed on the form. The general object of the present invention is to provide an improved method and apparatus whereby a stack of disc coils may be formed from an unbroken or continuous conductor and annular insulating collars interposed between adjacent coils without the necessity of splitting these collars and thus reducing their effectiveness as insulating barriers between the coils.

The invention will be described in connection with the accompanying drawing in which Fig. 1 is a view of a portion of a disc coil stack formed in accordance with the invention and a form of apparatus which may be used in forming the coil stack, Fig. 2 is a view similar to Fig. 1 but after one more coil has been formed in the stack, and Figs. 3, 4 and 5 indicate one method by which the coil stack may be formed.

Like reference characters refer to similar parts in both figures of the drawing. A winding formed in accordance with the invention, as indicated in the drawing, comprises a stack of disc coils with insulating collars interposed between adjacent coils. The coils are formed in succession from a continuous conductor 10 which is fed onto a cylinder 11, the cylinder being supported to rotate between a pair of centers 12 and 13 of a lathe. The first and alternate coils 14 thereafter are wound from their inner to their outer edges and the second and alternate coils 15 there-

after are wound from their outer to their inner edges. Thus the cross-overs 16 which connect adjacent coils are located alternately at the outer edges and at the inner edges of the coils. 55

After each coil is formed, an annular insulating collar 17 is placed next to it on the cylinder 11 so that adjacent coils are insulated from each other by these collars. It will be apparent and is obvious from the drawing that those cross-overs 16 which are at the outer edges of the coils 14 and 15 pass over the outer edges of their respective collars 17 while those cross-overs which are at the inner edges of the coils 14 and 15 are close to the surface of the cylinder 11 and pass through their respective collars. In accordance with the invention, therefore, the integral collars 17 are placed successively on the cylinder 11 in such manner that they alternately surround 70 and do not surround the conductor 10.

Before starting to form the winding, all the insulating collars 17 which are to be used between the coils 14 and 15 are supported around the lathe center at the opposite end 75 of the cylinder 11 from that at which the winding is to be started, this lathe center being long enough to extend through all these collars and support the cylinder. As shown in the drawing, the winding has been started 80 at the end of the cylinder 11 which is nearest the tail center 13 of the lathe so that all the insulating collars are supported around the head or driving center 12 before the winding is started. The collars 17 are supported by 85 two hooks 18 and 19 in two groups 20 and 21 of the same or approximately the same number.

The conductor 10 which is to form the winding is supplied from a drum or reel 22. 90 The end of the conductor 10 is withdrawn from the reel and passed through the group 21 of collars 17 nearest the cylinder 11 and the first coil 14 at the opposite end of the cylinder 11 is then wound. This first coil 14, as shown 95 in the drawing, is wound from its inner to its outer edge so that the first cross-over 16 will pass over the outer edge or outside of the first insulating collar 17. This first collar is therefore taken from the group 20 of collars 100

on the hook 18 and placed around the cylinder 11, being moved along the cylinder to a position close to the coil 14 which has just been wound. Insulating collars for this purpose 5 are generally made of flexible material such as pressboard so that those from the group 20 may be easily bent enough to permit them to be withdrawn through those in the group 21 and placed in position on the cylinder 11 10 without the necessity of splitting the collars.

The next coil, which is the first coil 15, is next wound from its outer to its inner edge so that the second cross-over 16 will be close to the surface of the cylinder 11 and must 15 pass through the next insulating collar 17 as shown in the drawing. After this coil has been formed, therefore, a collar is taken from the group 21 of collars on the hook 19, placed 20 on the cylinder 11 and moved close to the coil 15 which has just been formed. It is apparent that this collar also may be placed in 25 position on the cylinder 11 without splitting the collar.

The steps which have been described are 25 repeated until the winding has been completed. The drawing shows the winding about half completed. In Fig. 1, the last coil was wound from its inner to its outer edge and an insulating collar 17 is shown 30 as it is being transferred from the group 20 through the group 21 to its position on the cylinder 11 close to the coil just formed. Fig. 2 shows this insulating collar in place, the next coil wound from its outer to its inner 35 edge, and the next insulating collar as it is being transferred from the group 21 to its position on the cylinder 11. One method by which the coils 14 and 15 with the interposed collars 17 may be formed is indicated 40 in Figs. 3, 4 and 5. The coil stack or winding may be started, of course, from either end and formed in either direction, the method being exactly the same in either case. In 45 Figs. 1 and 2, the winding is shown as being formed from the right end toward the left and in Figs. 3, 4 and 5, it is shown as being formed from the left end toward the right. Each coil 14 is formed in the usual way by starting next to the cylinder 11 and winding 50 one turn upon another until the coil contains the desired number of turns. A collar 17 from the group 20 is then moved along the cylinder 11 to a position close to the completed coil 14, the conductor passing outside 55 the collar from the last or outer turn of the coil as shown in Fig. 3. The conductor is then taken in close to the cylinder 11 and a temporary coil 23 is next formed exactly like the coil 14, the turns progressing from 60 the inside to the outside turn. The conductor is then taken in close to the cylinder 11 again from the outer turn of the temporary coil 23 as shown in Fig. 4 and a coil 15 is formed by transferring the turns of the temporary 65 coil 23 to this new coil 15. Fig. 4 shows the

condition after two turns of the new coil 15 have been formed from the outer edge of the temporary coil. The turns are wound loosely enough in the new coil 15 so that after this coil has been formed it may be moved along the cylinder 11 to its permanent position close to the collar 17 as shown in Fig. 5. This will leave an extra amount of conductor in the cross-over 16. The new coil is then rotated through a small angle on the cylinder 11 to take up 70 this extra conductor in the cross-over 16 and to tighten the turns in the coil 15, this being done by pulling on the conductor where it leaves the inner turn of the new coil. A collar 17 from the group 21 which surrounds the 75 conductor 10 is then moved along the cylinder 11 to a position close to the coil 15 as shown in Fig. 5. The coils 14 and 15 are preferably spaced from the cylinder 11 by spacing strips 24 so that there is room for the conductor 80 10 between the cylinder 11 and the inner edge of the collar 17. The steps which have been 85 described may now be repeated until the entire winding has been completed.

The invention provides a convenient 90 method and apparatus for forming a continuous disc coil winding with integral insulating collars interposed between adjacent coils of the winding. While the invention has been described in what is now believed 95 to be its preferred embodiment, it will be apparent that various changes may be made within the scope of the invention as defined in the appended claims.

What I claim as new and desire to secure 100 by Letters Patent of the United States is:—

1. A method of forming a continuous disc coil winding with integral insulating collars interposed between adjacent coils, said method including passing a continuous conductor 105 through part of said collars to form the winding before said collars are assembled in the winding.

2. A method of forming a continuous disc coil winding with integral insulating collars interposed between adjacent coils, said method including passing a continuous conductor through one of two groups of insulating collars to form the winding, and assembling 110 said collars in the winding alternately from said two groups as said winding is formed.

3. A method of forming a continuous disc coil winding with integral insulating collars interposed between adjacent coils, said method including passing a continuous conductor through one of two groups of insulating collars, forming a stack of disc coils from said conductor by forming said coils with the conductor extending alternately from their inner to their outer and from their outer to their inner edges, and assembling said collars 115 in the winding alternately from said two groups as said winding is formed.

4. A method of forming a continuous disc coil winding with integral insulating collars 120

interposed between adjacent coils, said method including passing a continuous conductor through one of two groups of insulating collars, forming a stack of disc coils from said 5 conductor by forming said coils with the conductor extending alternately from their inner to their outer and from their outer to their inner edges, and assembling said collars in the winding alternately from said two groups as 10 said winding is formed, the collars from one of said groups being passed through the collars of the other of said groups to their positions in the winding.

5. Apparatus for forming a continuous 15 disc coil winding with insulating collars interposed between adjacent coils of the winding, said apparatus including a pair of lathe centers to support a cylinder upon which said winding may be formed, and means for supporting a plurality of insulating collars surrounding one of said lathe centers.

6. Apparatus for forming a continuous 20 disc coil winding with insulating collars interposed between adjacent coils of the winding, said apparatus including a pair of lathe centers to support cylinder upon which said winding may be formed, and means for separately supporting two groups of insulating collars surrounding one of said lathe centers.

30 In witness whereof, I have hereunto set my hand this ninth day of December 1927.

ING. PIETRO BOLIS.
